UNITED STATES PATENT OFFICE.

AMBLER TEES, OF PHILADELPHIA, PENNSYLVANIA.

KILN FOR ENAMEL-WORK.

SPECIFICATION forming part of Letters Patent No. 256,407, dated April 11, 1882.

Application filed March 8, 1882. (No model.)

To all whom it may concern:

Be it known that I, AMBLER TEES, a citizen of the United States, residing at Philadelphia, in the county of Philadelphia and State of Pennsylvania, have invented certain new and useful Improvements in Kilns for Enamel-Work, of which the following is a specification, reference being had therein to the accompanying drawing.

10 This invention relates to new and useful improvements in porcelain-kilns for enameling work for decorative, dental, and other purposes; and the novelty consists in the construction of the same, as will be hereinafter more 15 fully described, and particularly pointed out in the claim.

The figure in the drawing is a view in perspective and partly in section, showing the exterior as well as the interior of my invention.

20 A is the base, provided with a removable grate, a, and door a'.

B is the muffle-chamber, and is provided with a door, b, by which access may be had to the interior of the muffle C.

25 D is the upper section or roof, and on the top of which is the smoke-stack d; and d' is the door through which the fuel, consisting of broken coke or coal, is placed in the furnace, which is filled up so as to completely cover the muffle C.

In operation the denture to be enameled is 30 placed in the muffle C and the fire started. The heat may then be readily regulated or steadily maintained by adjusting the doors a' and b, and as the whole device, with the exception of the grate, is made of fire-proof material, a very 35 high degree of heat may be employed. In ordinary manufacture I construct it about fifteen inches high, twelve long, and about eight wide, so that in size it is small, convenient, and economical, and radiates little or no heat into the 40 laboratory, and is therefore admirably adapted to the purpose used.

Having thus fully described my invention, what I claim as new and useful, and desire to secure by Letters Patent of the United States, is— 45

A portable kiln for enamel-work, consisting of the base A, having grate a and door a', the muffle-chamber B, provided with muffle C, having door b, and the roof-section D, having the fuel-feeding door d', constructed and operating substantially as and for the purpose set forth.

In testimony whereof I affix my signature in presence of two witnesses.

AMBLER TEES.
